LIGHT SUPPORT

Frank C. McGrady, Washington, D. C.

Application October 20, 1933, Serial No. 694,496

3 Claims. (Cl. 248—159)

This invention relates generally to improvements in supports, and more in particular to an improved means for supporting electric flood lights.

5 My invention is capable of many uses particularly where a relatively tall or long support is required. One important use has been found to be in connection with electric flood lamps.

Powerful electric lamps between 500 and 2000 10 watts are supported at the tops or ends of supports ranging from 15 to 35 feet in length. These lamps are usually provided with reflectors and are used to illuminate gasoline stations, outdoor parking lots, athletic fields, exhibit houses, and 15 for numerous other purposes.

The supports for such lamps can be made of any suitable material but are usually tubular pipes of steel. The bases of these pipes must be fairly large and strong, in order to not only support 20 the lamp structure and reflector but to withstand additional strain when it is necessary to service the lamps.

A reflector is provided at the top of these supports for the lamp. Unless the reflector is 25 maintained bright and clean the efficiency of the lamp is greatly impaired and the illumination desired is not had. It is necessary therefore to clean and polish these reflectors at frequent intervals. Additionally, these lamps require other 30 service in the form of new lamp bulbs, refinishing of the reflector, focusing of the reflector, checking of the wires, etc. The supports are also painted at frequent intervals, which ordinarily requires 35 the services of an expert steeplejack or painter.

These lamps, as mentioned before, are usually 15 to 35 feet from the ground and the present way of 40 reaching them for servicing is by a long ladder. The weight of the ladder plus the weight of the workman puts an unusual load upon the lamp support, particularly at the base, so it is necessary to make the support, and particularly the base, of good size pipe to withstand this strain, which heretofore usually ranged from 2½ to 4½ 45 inches in diameter.

The cost of such supports is quite appreciable, and the added expense of having the lamps 50 serviced by a skilled workman who must be willing to take the dangerous risks incident to reaching the top of the lamp support by a ladder all goes to make the use and maintenance of such lamps fairly expensive.

I have invented a new type of support particularly adapted for such lamps which makes the initial cost much lower, and which can readily 55 be serviced and painted by any unskilled

person from the ground without danger, and the need of a serviceman trained in this particular field is no longer required with my improved support. Moreover, my improvement in lamp supports readily adapts itself to incorporation 5 with the old forms of supports enabling the lamps thereof to also be easily accessible for servicing, and so dispensing with the need of an expert serviceman and reducing the cost of maintenance.

Briefly, my invention generally consists of providing a supporting standard for electric lamps of the type hereinafter described made up as several longitudinal sections and joined by a special coupling member, wherein the support may be of smaller diameter, lighter and of less 10 expensive materials than heretofore, and provides means for rendering the end or top of the support, including the lamp and reflector, accessible for servicing from the ground and without need of a ladder. An inlet or junction box 15 is provided in combination with the support which can be used to splice the wires leading to the lamp, and also used as a junction and splice box 20 to carry the conduit and wire to other similar structures or electrical outlets.

25 In the accompanying drawing I have illustrated a practical use of my invention, in which:

Fig. 1 is a vertical cross-sectional view of a portion of a lamp support of the type under consideration and illustrates the upper and lower 30 supports and hinge means for allowing the upper support to be rendered accessible;

Fig. 2 is a horizontal cross-sectional view taken through line 2—2 of Fig. 1 showing the hinge, and additionally shows in dotted lines inlet and 35 outlet conduits for the electric wires leading to the lamp;

Fig. 3 is a segmental cross-sectional view taken on the vertical line 3—3 and the horizontal line 4—4 of Fig. 2 and shows one of the electric wire 40 conduits, namely the inlet; and,

Fig. 4 is a side view of the entire lamp supporting structure, and in dotted lines is illustrated the upper support lowered for servicing the lamp.

A lower support of any approved nature illustrated here as a tubular pipe 10 is securely anchored in the ground. The upper end of the pipe 45 engages and fits into a block B, which is the lower of two similarly formed block members which together constitute a novel coupling member, 50 the other being marked B'.

The lower block B is formed with a central bore and has an internal flange 11 provided on its lower side with a seat 12 for the upper end of pipe 10. The bore is tapered as at 13 to assure 55

a stable fitting with pipes or other types of base members of varying sizes. Depending from the lower side of the block is a skirt 14 spaced from the pipe, and through which screws 15—15 pass 5 to lock and retain the pipe in position. A packing weld, or braze, 16 between the skirt and pipe is provided if desired to keep out moisture. One side of the block carries the apertured hinge lugs 17—17 so positioned as to align with the 10 apertured hinge lugs 18—18 of the upper block B'. A bolt 19 passes through the apertures in the aforementioned lugs to constitute a hinge connection between the two blocks. A tight fit should be effected between the abutting faces 15 of these blocks to prevent the intervention of moisture, and to effect that end their faces may be machined as shown or provided with a gasket plate.

Upper block B' likewise has a central bore and 20 has an internal annular flange 20 forming a ring seat 21 for the lower end 22 of the upper lamp support 23. The block further has a portion of its bore tapered as at 24 for the purpose above mentioned. Likewise an upstanding skirt 25 is 25 integral with the block and is provided with screws and a packing associated therewith in the same manner and for the same purpose as in the construction of the lower block B.

Bolt holes are drilled in vertical alignment 30 through both upper and lower blocks to receive the several bolts as shown at 26, which constitute one means of locking the blocks together and maintaining the lamp support in a rigid and operative position.

35 The support in the present instance being tubular forms a housing for the wires leading to the lamp. The lower block B includes vertical bores 30 and 31 which connect with the horizontal channels 32 and 33 which are cut in the top 40 surface of the block and lead to the interior of the support.

Fig. 3 shows one of such vertical bores, namely the inlet bore 30, and its connecting horizontal channel 32. The internal edges of the two blocks 45 adjacent the bores and channels are rounded as at 34 to prevent cutting of the electric wires.

The lower end of the bores 30 and 31 are preferably screw threaded to receive the electric wire conduits 35 and 36 which are likewise preferably 50 screw threaded at their upper ends to effect a convenient fitting therebetween.

Fig. 4 shows use and adaptation of the invention in its assembled form with the lower pipe 55 10 anchored in the ground and supporting the block B, with block B' hingedly mounted thereon and supporting the upper support 23 which carries the lamp and reflector. If for any of several reasons it is desired to service the lamp, 60 as by polishing the reflector, replacing a lamp bulb, or checking the wiring, it is only necessary in this instance to remove the several bolts 26 from the two blocks and lower the upper support 23 until the top rests upon the ground, 65 which position is partially shown in dotted lines by Fig. 4. This will enable the workman to have full access to the lamp reflector and all wiring in a safe manner without any of the dangerous risks of climbing a ladder as has been heretofore 70 necessary. When the operation is complete the upper support and the lamp can again be raised to the position shown in full lines, and the bolts 26 replaced to securely lock the structure in position.

75 To assist in lowering the upper supporting

structure it may be desired to secure a chain or cable to the top of the support as shown at 40 and when not in use it could hang by the side of the support, or be anchored to a ring 41 in the ground.

5 In a support of this type it will be readily appreciated that the entire supporting structure can be of much lighter material, thus reducing the cost, as the strength formerly necessarily inherent to such structures is no longer needed due 10 to the improved manner of rendering the lamp and reflector accessible.

The improved means above described for enabling the lamp to be serviced may also be readily incorporated in a lamp support of the old type, wherein the base of the support is relatively thick for the reasons explained. It is only necessary to cut the support through on a horizontal plane a few feet above the surface of the ground, 20 and attach a block of the type described as B to the top of the lower support portion, and a block such as B' to the lower end of the upper supporting portion, insert a bolt of the type described at 19, hoist the support into position and lock in place by the bolts 26.

25 Thus it will be appreciated that I have invented a new and improved support means for electric lamps of the type under consideration, 30 wherein the cost of production and upkeep of the lamp and support is greatly reduced, and which adapts itself to the old type of lamps to lessen the upkeep thereof.

35 While I have shown and described my invention as being particularly adapted for use in conjunction with flood lamps, it is to be understood 40 that the same is not so limited as it is adapted for use in all instances wherein a relatively tall vertical support is desired, and wherein it is necessary from time to time to lower said support 45 for the purpose of servicing.

50 While in the drawing and description of the invention I have illustrated my improved support as used in a vertical position, it should be understood that the support readily adapts itself for 55 use in any other angular position. For instance, the base could equally as well be anchored to a vertical wall with the support extending outwardly therefrom in a horizontal plane. Such a position would be most desirable for use in connection 60 with illuminating large signs on the sides of buildings, etc. In such a use the hinge construction would be accessible from a window in the building, and by means of the cable attached to the outer end of the support, the lamp and reflector could be drawn up to assume a horizontal 65 position at right angles to the base support and parallel to the building wall, in which position the lamp and reflector would be most accessible 70 from an upper window for servicing, and the junction box open for inspecting the wiring.

75 I claim:

1. A support for a flood lamp of the type described comprising a base member and a top member, a pair of complementary hingedly connected blocks mounted upon the base member for support of the top member, tubular skirts fixed to said blocks and positioned on opposite sides thereof for the reception of said base and top members, and a bore extending centrally through said blocks having a flange therein for supporting on opposite sides thereof said base and top members, said bore and flange cooperating to support said base and top members in spaced relation.

tion with respect to said skirts, and means to secure said base and top members in position.

5. A support for a flood lamp of the type described, comprising a pair of complementary hingedly connected blocks, skirts fixed thereto, bores formed centrally of said blocks and having a shoulder therein, a base member extending into the skirt and bore of one of said blocks and abutting the under side of the shoulder thereof to support the same, a lamp supporting top member extending into the skirt and bore of the other of said blocks and supported by the shoulder formed therein, and means to lock said blocks in position to cause the same together with said base and top members to assume a lamp supporting position.

10. A support for an electric flood lamp of the type described comprising a base member and a top lamp supporting member, and the combination therewith of a hinged connection between

said members including a junction box for said lamp, the same comprising a block having a skirt fixed to the block on one face thereof concentrically disposed about an end of said base member, a central bore in said block and a shoulder formed therein for supporting said block upon said base member, a second block member hingedly connected to said first block and formed with a skirt portion on one face thereof concentrically disposed about an end of said top member, and provided with a bore formed centrally thereof and for alignment with the bore of said first block, a shoulder in said bore for supporting the end of said lamp supporting member, means for locking said blocks in place, and a channel formed in 15 one of said blocks opening into the bores thereof for accommodating the wires of said lamp and constituting with said blocks a junction box.
